RACK FOR HOLDING LIFE BUOY EQUIPMENT

Joseph G. A. Riccio, Bristol, R. I.

Application March 18, 1950, Serial No. 150,520

1 Claim. (Cl. 114—190)

1 This invention relates to improvements in racks for holding life buoy equipment and it has for its primary object to provide a rack unit of the class described which will normally hold both a life buoy ring and its throw-line in compactly assembled relationship and in such manner that they are always accessible for expeditious removal and use.

A further object of the invention is to provide a rack of the class described from which the life buoy and its throw-line may be quickly removed by an individual without the necessity of operating unfamiliar and more or less complicated fastening devices.

A further object of the invention is to provide a rack of the class indicated of simple and inexpensive construction whose parts will not be injuriously or adversely affected by weather conditions.

To these ends I have provided a rack of the class indicated which, in its preferred form, may be constructed and used as set forth in the following description, the novel features thereof being pointed out and defined in the claim at the close of the description.

In the accompanying drawings:

Figure 1 is a front elevation of my improved rack for holding life buoy equipment.

Figure 2 is a side elevation, partly in section, of the rack shown in Fig. 1.

Figure 3 is a front elevation, partly broken away, of the rack after applying thereto the life buoy and throw-line as hereinafter described.

Figure 4 is a side view, partly in section, of the loaded rack shown in Fig. 3.

The illustrated embodiment of my invention comprises a vertically elongated frame in the form of a panel 10 which may be made from waterproofed wood, metal or other suitably rigid material. The upper portion of this panel or frame is provided with marginal apertures 11 for the reception of bolts, screws or other appropriate means by which said panel is fastened securely to any suitable and convenient supporting fixture such as that indicated by broken lines at 12 in Fig. 4 of the drawings, which fixture may be located on board a ship or on a shore or wharf in proximity to a body of water.

Rigidly fastened by screws 13 in position upon the outer face of the panel 10 in proximity to the upper end thereof are two outstanding horizontally aligned upwardly directed hooks 14 which are spaced apart equidistantly from a longitudinal medial line extending vertically from the top to the bottom of the panel. As shown in Figs. 3 and

4 these two hooks are adapted to extend through and support an annular life buoy 15.

Directly below the pair of hooks 14 the lower portion of panel 10 is made upon its outer side with vertical guides or ways 16 within which are slidably confined the opposite side marginal portions of a slide 17 and rigidly fixed in position upon the outer face of this slide by screws 18 is a downwardly directed outstanding hook 19 that is disposed upon the longitudinal medial line of panel 10.

The slide 17 herein shown is made from lead so that its weight and that of hook 19 yieldingly urge said slide and hook downwardly, the limit of 15 the movement of the slide in that direction being determined by a stop herein shown as a cross-bar 20 at the bottom of the ways 16.

To the life buoy 15 is fastened as at 22, Fig. 3, one end of the usual throw-line 21 and before 20 applying the life buoy to the two hooks 14, said line is wound around all three hooks as shown after which the life buoy is applied to the two hooks 14 with its lower portion resting against the coiled throw-line so that it assists in holding 25 the latter in engagement with the three hooks as will be clear from Fig. 4. The outer end portions of the two hooks 14 extend obliquely upwardly from the shank portions of said hooks to provide a shoulder for holding the upper portion 30 of the throw-line coil in position upon said hooks, while the outer end portion of the lower hook 19 extends obliquely downwardly from the shank portion of said hook to provide a shoulder for holding the lower portion of the throw-line coil 35 in engagement with said hook.

The throw-line 21 may be coiled in either direction around the three hooks starting with the loose end 23 thereof (Fig. 3) disposed alongside 40 of the lower hook 19 and when it is completely coiled upon the hooks the life buoy 15 is hung upon the two upper hooks 14 as shown.

To use the life buoy and throw-line the life buoy is lifted clear of the hooks 14 by means of one hand preparatory to throwing the buoy while 45 grasping the free end 23 of the throw-line with the other hand whose fingers are hooked under and behind the coil adjacent to hook 19 and utilized to lift the latter and its slide 17 so that the upper portion of the coil can be removed from hooks 14 whereupon the lower part of the coil will clear the hook 19. The throw-line coil is then permitted to drop upon the deck or ground and the life buoy is thrown while the free end 23 of the line is held by the thrower or otherwise.

The above described rack is of simple and in-

expensive construction and while in use serves to hold the buoy and throw-line in compact and orderly fashion and in such manner that they can be removed for use with ease and dispatch without requiring time-consuming operation of complicated fastening devices.

An advantage to the above described rack characterized by having the throw-line wound around the hooks as above described, is derived through the fact that when the coil is removed from said hooks and thrown properly upon the ground or deck, the buoy 15 is connected with the top of the coil so that when the buoy is thrown out into the water the line will, without entanglement, render freely from the top of the coil and will not become snarled.

What I claim is:

A rack for holding life buoy equipment, comprising a frame for attachment in an upright position to a fixture, two horizontally aligned spaced-apart hooks fixedly connected to said frame, said hooks directed upwardly and outwardly from said frame and adapted to support an annular life buoy and an associated coil of life line thereon, vertical ways in said frame disposed beneath said

5

hooks and spaced below the position occupied by the buoy, a weighted slide positioned in said ways and a third downwardly and outwardly directed hook fixedly secured to said slide for movement therewith toward and away from said first mentioned hooks and cooperatively associated therewith to engage and releasably hold the coiled life line.
